FLUID-COOLED ELECTRODE HOLDER

Homer A. Jackson, Detroit, Mich.

Application June 10, 1942, Serial No. 446,417

18 Claims. (Cl. 219—8)

This invention relates to welding electrode holders and particularly to a holder of this type having means for cooling the same in use.

It is well known that in welding operations extremely high temperatures are encountered and holders employed for gripping the electrodes become hot and uncomfortable to use. The holder is provided with a handle of electric insulating material and although this does help to reduce the transmission of heat to the hand of the operator it is usually ineffective when the holder is operated for long periods of time or when the electrode is used to a point close to the holder.

An important object of this invention is to provide a novel electrode holder having means therein providing for the passage of cooling fluid. The holder is so constructed that it is cooled in use throughout its entire length, including the handle which is grasped by the hand of the operator. Another important object of this invention is to provide a fluid cooled holder which is economical to make and assemble and which even with the provision of the fluid cooling means weighs little if any more than a holder without this feature.

An important feature of the invention is the provision of means for cooling not only the gripping means for holding the electrode but also the insulated handle which is grasped by the operator. A novel provision is made for directing a portion at least of the cooling fluid upon the insulating handle. The fluid cooling medium which is preferred is air under pressure. At one point in its travel air is directed against surfaces of the handle and preferably against the inside surfaces thereof. Preferably the cooling air after passage through the electrode gripping sections of the holder is allowed to discharge freely inside the holder and in such a direction against the inside surfaces thereof as to maintain the same at a reduced comfortable temperature.

In one form of the invention, a novel economical method of construction and assembly provides a circulating air passage in the interior of one of the members which grips the electrode. The air circulating system is thus effectively concealed and protected. In another form of the invention, a separate tube is provided on the outside of the same member. The novel provision of a groove around the member provides a recessed seat in which the tube is protectingly received. In either form of the invention, the discharge end of the air passage opens out inside the insulating handle. Preferably, an apertured

tube closed at its outer end forms an extension to the discharge end of the passage and serves to direct the air discharging therefrom laterally toward the inside walls of the handle.

Various other objects, advantages and meritorious features will become more fully apparent from the following specification, appended claims, and accompanying drawings, wherein:

Fig. 1 is a view showing a holder of the type described herein connected to a source of air pressure.

Fig. 2 is a longitudinal sectional view of a holder embodying features of the invention.

Fig. 3 is a longitudinal sectional view of the holder at right angles to that in Fig. 2 and along line 3—3 thereof.

Fig. 4 is a transverse sectional view of the holder along line 4—4 of Fig. 2.

Fig. 5 is a transverse sectional view of the holder along line 5—5 of Fig. 2.

Fig. 6 is a transverse sectional view of the holder along line 6—6 of Fig. 3.

Fig. 7 is a side view, partly in section, of a modified holder embodying features of the invention.

Fig. 8 is a longitudinal sectional view along line 8—8 of Fig. 7, and

Fig. 9 is a transverse sectional view along line 9—9 of Fig. 8.

For illustrative purposes the invention is embodied in electrode holders of the type shown in my Patent No. 2,003,196. It is understood that the invention is applicable to other types of holders and that it may be modified to suit different conditions.

Referring specifically to the drawings, the holder is provided with means for gripping an electrode. This means in the illustrated type of holder comprises a pair of jaw members 10 and

12. One jaw member, 10, has a widened end section 14 which is received in a tubular or sleeve-like handle 16 of electrical insulating material. The other jaw member 12 is pivotally connected through the medium of a transverse

pin 18 to the jaw member 10. It is upwardly bent as it extends toward the handle and means in the form of a coil spring 20 enclosed in telescoping insulating cups 22—24 serves to yieldingly space the jaws apart at this point in order to cause the outer or forward sections of the jaws to press together. Grooved plates 26—28 are provided on the inner jaws of the outer ends to tightly clamp an electrode therebetween.

The tubular handle 16 is removably attached to the end section 14 of the member 10 in any

suitable way, such as by screw 28. The handle projects beyond the end of the member a substantial distance. A cavity 30 is formed in the center of the end section 14 and receives the terminal end of an electric cable 32. The latter may be soldered in place or held in the cavity by a set screw 34. The cable enters the open rear end of the handle. Over the jaw members there are provided insulating pieces 36 of the type described and claimed in my aforesaid patent. These insulating pieces are preferably channel-shaped as shown and protect the sides as well as the outside top and bottom surfaces of the members.

The present invention relates to the provision of means for cooling the holder by a fluid medium. A conduit is provided which forms a circulatory system through which the cooling medium is passed. In the embodiment of the invention in Figs. 2 to 6 the conduit is in the form of a passage formed inside one of the jaw members. In the embodiment of the invention illustrated in Figs. 7, 8 and 9 the conduit takes the form of a separate tube running along the side walls of one of the jaw members.

In the first embodiment of the invention the conduit is represented by the passage 38 extending through the member 10. The passage extends from the end of the member in the handle toward the opposite end, and at a point short of the latter it makes a 180° bend and returns to the end in the handle. The passage is generally U-shaped with the ends opening out through the end in the handle on opposite sides of the cable receiving cavity 30. As is evident in the sectional views, Figs. 4, 5 and 6, the passage is deep within the member 10. It is preferably formed in the process of manufacture by making the member 10 of two longitudinal sections provided on their confronting faces with registering grooves which together form the passage. The two sections are welded or otherwise joined together to form an integral member. The division line between the two sections of member 10 is along the section line 3—3 of Fig. 2. Fig. 3 is therefore a frontal view of the bottom longitudinal section as it would appear prior to being joined to the upper section. The sections of member 10 are preferably cast with the grooves in corresponding positions for registration.

The cavity 30 which receives the end of the cable is similarly formed. A semi-circular recess is formed in each longitudinal section of the member 10 at the rear end portion thereof and opening out through the rear end. The two recesses together form the cavity 30 when the two sections of the member 10 are welded together. The extremities of the passage 38 are slightly jogged to pass around the cable cavity and extend along opposite sides thereof as is evident in Fig. 3. The passage is also arranged to pass around and between the stud pins 40 which are used to secure the clamping plate 26 to the other end of member 10.

As previously mentioned, this invention is adapted for cooling by a gaseous medium such as air. Air is delivered under pressure to one end of passage 38 and caused to travel therethrough. Fitted in one end of passage 38 is an inlet pipe or tube 42 which forms an extension of the passage and preferably extends to a point adjacent the end of the handle. To the outside extremity of this tube there is detachably connected a flexible hose 44 which communicates with a source of fluid pressure, such as the air

compressor unit shown generally at 46 in Fig. 1. Air pressure delivered by this unit enters one end of the passage 38 and flows therethrough and discharges from the other end thereof.

It is an important object of this invention to provide means which directs at least a portion of the cooling medium upon the insulating handle 16 and thereby maintain the same at a relatively reduced temperature while the holder is in use. Preferably this is accomplished by providing a special device which receives the air discharging from the outlet end of the passage 38 and directs the same against surface portions of the handle. In the illustrated embodiment of the invention in Figs. 1 to 6, this is accomplished by the provision of a tube 48 having a series of apertures 50 in the side wall thereof. This tube forms an extension to the discharge end of the passage 38 but preferably terminates first inside the rear end of the handle where it is inconspicuous. It is desirable to close the end of the tube 48 by a suitable plug 52 in order to direct all the air laterally from the tube. It is obvious that when air is forced under pressure through the discharge end of the tube it will continuously discharge from the apertures in the tube 48 directly against the inside surfaces of the handle and cool the same. The air will be relatively cool even though it has passed through the hottest region of the holder. The sudden release or reduction of pressure as it escapes from the apertures 50 acts to reduce the temperature of the air.

Although an apertured tube of the kind described is preferred for cooling the handle, it is understood that other means may be provided for using the air delivered to the holder. For example, the inlet tube might be constructed to discharge a portion of the air delivered to it into the handle before entering the passage 38. Instead of the apertured tube 48, other means might be substituted for using the return air for cooling the handle. All or a portion of the return air might be conducted to a point outside the handle and blown directly on the outside surface of the handle and the hand of the operator holding the same. The tube 48 itself might be extended beyond the end of the handle and bent to direct the air upon the outside of the handle. All these and other modifications fall within the scope of the invention which is to utilize the air conducted to the electrode gripping parts of the holder for also cooling the handle and the hand of the operator.

In Figs. 7 to 9 a modification of the invention is shown which uses a separate tube for the fluid cooling conduit throughout its length. Referring to the drawings, the assembly of the electrode holder is generally the same as previously described and like parts are similarly numbered. The fluid conduit in this instance comprises a long tube 56 which extends along both sides and around the end of the jaw member 10. The latter, in this modification, is cast in one piece. It is, however, provided with a longitudinal groove 62 along each side and around the front end thereof. The groove is of a size and depth to completely receive the tube. The lateral dimensions of the holder are thereby not increased by this provision. The channeled insulating material 36 extends over the grooves and the tube concealing these elements from view and protecting them in use.

The groove 62 and the tubes are jogged slightly in the end received in the handle in order to

clear the cable receiving hole 38 on both sides thereof. The ends of the tube 68 project beyond the cable end of the jaw member 10. One end 64, corresponding to tube 42 previously described, serves as the inlet and is adapted to be connected to a flexible fluid pressure hose. The other end 68 is closed off and perforated similarly as tube 42. It is obvious that the modification in Figs. 7, 8 and 9 will function similarly to that described for the modification in Figs. 1 to 6.

What I claim:

1. A welding electrode holder including, in combination, a member which cooperates with other means for holding an electrode, an insulating handle attached to one end of said member, a fluid conduit associated with said member and extending from inside the handle to the opposite end of the member and returning to the handle, and means for introducing fluid under pressure to one end of the conduit in said handle, and means associated with the other end of the conduit for discharging the fluid outwardly toward the inside wall of the handle.

2. A welding electrode holder comprising, in combination, a member adapted to cooperate with other means for holding an electrode, a sleeve-like handle of insulating material attached to and surrounding one end of said member, a channel shaped sheath of insulating material covering the opposite end of said member with the exception of its electrode engaging face, a cooling fluid conducting conduit extending longitudinally along said member between the member and the insulation material from the end inside the handle to the opposite end and returning to the end inside the handle, and means for delivering cooling fluid into one end of said conduit inside the handle.

3. A welding electrode holder comprising, in combination, a member adapted to cooperate with other means for holding an electrode, a sleeve-like handle of insulating material attached to one end of said member, a conduit extending longitudinally through said member from the end inside the handle to the opposite end and returning to the end inside the handle, a source of air pressure, and means connecting said source of air pressure with one end of the conduit inside the handle, and means associated with the other end of the conduit inside the handle for discharging the air leaving the conduit radially toward the inside surface of the handle.

4. A welding electrode holder comprising, in combination, a member adapted to cooperate with other means for holding an electrode, a sleeve-like insulating handle secured over one end of said member and projecting therebeyond, a conduit associated with said member extending from the end inside of said handle to a point short of the opposite end and returning to the end inside the handle, means for delivering fluid under pressure to one of the ends of said conduit in the handle and causing the same to travel through the conduit and return to the other end of the conduit inside the handle, and a tube section in that portion of the handle projecting beyond said member forming an extension to the discharge end of the conduit and provided with one or more openings in its circumference for discharging the fluid toward the inside surface of the handle.

5. A welding electrode holder comprising, in combination, a member adapted to cooperate with other means for holding an electrode, a sleeve-

like handle of insulating material enclosed over one end of the member and projecting therebeyond, a conduit extending from the end of the member inside the handle to a point short of the opposite end and returning to the end inside the handle, and a section of tube forming an extension to one end of the conduit and projecting beyond the end of the member inside the handle, said tube section provided intermediate its length with a series of openings.

6. A welding electrode holder comprising, in combination, a member adapted to cooperate with other means for holding an electrode, a sleeve-like handle of insulating material secured to one end of said member and projecting therebeyond, a conduit extending substantially the length of the member from the end inside the handle to a point short of the opposite end and returning to the end inside the handle, a pair of tubes attached to the end of said member inside the handle and forming extensions of the conduit, one of said tubes projecting to a point adjacent the end of the handle and being open-ended for coupling to a source of fluid supply, the other tube terminating short of the end of the handle and having its outer end at least partially closed against the escape of fluid therefrom, and one or more openings in the side of said last mentioned tube.

7. A welding electrode holder or the like having a handle which is grasped by the hands of the operator and gripping means for holding an electrode extending from the handle, means for cooling the interior of the gripping means including a cooling fluid passage extending therethrough, said cooling fluid passage having its discharge end opening into the interior of said handle whereby cooling fluid caused to be passed therethrough to cool said gripping means will also serve to cool the handle.

8. A welding electrode holder or the like having a handle which is grasped by the hands of the operator and gripping means extending from one end of the handle for holding an electrode, a cooling fluid passage associated with said gripping means through which cooling fluid may be passed to cool the same, said cooling fluid passage discharging into the handle, and means in the handle for directing cooling fluid thus discharged toward the inside surfaces of the handle.

9. A welding electrode holder or the like having a handle which is grasped by the hands of the operator and gripping means extending from one end of the handle for holding an electrode, a cooling fluid passage associated with said gripping means having its inlet and outlet in the handle, means for delivering cooling fluid to the fluid inlet of said passage, and means for directing cooling fluid discharging from said outlet laterally toward the sides of the handle.

10. A welding electrode holder including a handle of insulating material and a member projecting therefrom adapted to cooperate with other means for holding an electrode, said member formed of two longitudinally abutting parts having their abutting faces correspondingly grooved to form a fluid passage extending from the end in the handle to a point short of the opposite end and returning to the end in the handle.

11. A welding electrode holder including a sleeve-like handle of insulating material and means projecting from one end thereof for gripping an electrode including an elongated mem-

ber having one end received in the handle, said member formed of two longitudinal parts brought into abutment and provided on their abutting faces with registering grooves forming a passage extending from the end in the handle to a point short of the opposite end and returning to the end in the handle, and a tube attached to the end of the member in the handle and forming an extension of one end of said passage, said tube provided with one or more openings in the side thereof.

12. A welding electrode holder comprising, in combination, a pair of jaw members adapted to cooperate with one another to hold an electrode, one of said jaw members formed of two cast metal longitudinally abutting parts having their adjacent faces provided with registering grooves forming cooling fluid passage extending substantially the length of the member, means which is grasped by the hand of the operator for using the holder, means for supplying cooling fluid to one end of the cooling fluid passage to cause the fluid to pass therethrough, and means at the other end of said cooling fluid passage for directing the cooling fluid flowing therefrom upon said hand grasping means.

13. A welding electrode holder comprising, in combination, a member adapted to cooperate with other means for holding an electrode, a handle enclosed over one end of said member, a tube leading from within said handle extending along one side of said member and around the exposed end thereof and returning along the other side of the member and entering the handle, means for supplying cooling fluid to one end of the tube to cause the same to travel the length thereof and return to the handle, and means in the handle for directing cooling fluid discharging from the other end of the tube upon the handle.

14. A welding electrode holder comprising, in combination, a member adapted to cooperate with other means for holding an electrode, a sleeve-like handle of insulating material enclosing one end of said member and projecting therebeyond, said member provided with a longitudinal groove extending along both sides and around the other end of the member, a metal tube arranged in said groove so that it follows the groove around the member and the ends thereof enter the handle, means for connecting one end of said tube to a source of cooling fluid, and means on the other end of the tube for directing the cooling fluid discharging therefrom laterally toward the inside walls of the handle.

15. A welding electrode holder comprising, in

combination, a cylindrical insulating handle portion, an electrically conductive member mounted within one end of the handle portion and projecting therebeyond forming an electrode gripping jaw portion, said member provided with a cooling fluid passageway, an electric cable entering the opposite end of the handle and secured to said member therein, said handle portion having a substantial part of its length forming a jacket spaced from the cable beyond the end of said conductive member, and means for directing cooling fluid into the cooling fluid passageway of said member and for discharging cooling fluid therefrom directly into said jacket portion of the handle.

16. A welding electrode holder comprising, in combination, a cylindrical insulating handle portion, an electrically conductive member mounted within one end of the handle portion and projecting therebeyond forming an electrode gripping jaw portion, an electric cable entering the opposite end of the handle and secured to said member therein, said handle portion having a substantial part of its length forming a jacket spaced from the cable beyond the end of said conductive member, said member provided with a cooling fluid passage extending linearly therethrough adjacent to the insulating handle, and means for directing cooling fluid through said passage and discharging same into the jacket forming portion of the handle.

17. A welding electrode holder comprising, in combination, an electrically conductive member, an electric cable connected to one end of said member, the other end of said member adapted to serve as an electrode gripping jaw, insulation material covering two opposed sides of said member, a fluid cooling passageway extending along said two opposed sides of said member underneath and adjacent to the insulation material, and means for delivering fluid into one end of said passageway.

18. A welding electrode holder comprising, in combination, an electrically conductive member, an electric cable connected to one end of said member, the other end of said member adapted to serve as an electrode gripping jaw, insulation material partially enclosing said member and defining therewith a cooling fluid passageway arranged between the insulation material and said member, and means for delivering cooling fluid into said passageway to cool said member and the insulation material.

HONEL A. JACKSON.
